US0D1064186S

(12) **United States Design Patent** (10) Patent No.: **US D1,064,186 S**
(45) Date of Patent: ** Feb. 25, 2025

(54) **SOAP DISPENSER**

(71) Applicant: **Taizhou Shiwang Cleaning Equipment Co., Ltd.**, Zhejiang (CN)
(72) Inventor: **Jinxi Xie**, Zhejiang (CN)

(**) Term: **15 Years**

(21) Appl. No.: **29/951,242**

(22) Filed: **Jul. 9, 2024**

(51) LOC (15) Cl. 23-01
(52) U.S. Cl.
USPC **D23/225**

(57) **CLAIM**

The ornamental design for a soap dispenser as shown and described.

DESCRIPTION

FIG. 1 is a perspective view of a soap dispenser showing my new design;

FIG. 2 is a second perspective view thereof;

FIG. 3 is a third perspective view thereof;

FIG. 4 is a front elevational view thereof;

FIG. 5 is a rear elevational view thereof;

FIG. 6 is a left side view thereof; and,

FIG. 7 is a right side view thereof.

The broken lines illustrate portions of the soap dispenser that form no part of the claimed design.

1 Claim, 7 Drawing Sheets
